DESIGN.

—o—

A. F. JACKSON.

FORK OR ANALOGOUS ARTICLE.

No. 15,586.

Patented Dec. 2, 1884.

Fig. 1.

Fig. 2.

UNITED STATES PATENT OFFICE.

AUSTIN FREDERICK JACKSON, OF TAUNTON, MASSACHUSETTS, ASSIGNOR
TO REED & BARTON, OF SAME PLACE.

DESIGN FOR A FORK OR ANALOGOUS ARTICLE.

SPECIFICATION forming part of Design No. 15,586, dated December 2, 1884.

Application filed July 22, 1884. Term of patent 7 years.

To all whom it may concern:

Be it known that I, AUSTIN FREDERICK JACKSON, of Taunton, in the county of Bristol and State of Massachusetts, have invented and 5 produced a new and original Design for Forks or Analogous Articles, of which the following is a specification, reference being had to the accompanying drawings, forming part thereof.

10 Figure 1 is a front view, and Fig. 2 a back view, of a fork, showing my new design.

The handle is formed in outline with a very gradual taper from the shank to a point near its end, from which widest point it is slightly 15 contracted to the end, which terminates abruptly with a nearly-square finish with slightly-rounded corners.

10 The front surface of the handle A of the fork has a continuous marginal bead, B. The upper 20 portion, C, of the space within the bead, being nearly one-half the length of the handle, is plain or unfigured, while the remaining portion is ornamented by a series of raised tapering corrugations, D, said corrugations being made 25 tapering from the ends toward their centers, and being crossed transversely near their centers by a ribbed band, E.

I am aware that it is not new to form longitudinal corrugations on the shank or smaller portion of a spoon or fork handle, which corrugations are crossed by transverse bands. 30

My design for the handle is distinct, as a whole, the upper half of the handle being perfectly plain, with the exception of a marginal bead, and the lower half having parallel 35 tapering corrugations increasing in length toward the middle one, which is the longest, and which corrugations are crossed by a transverse band at the smallest portion of the shank of the handle. 40

What I claim is—

A design for the handle of a fork or analogous article of the shape shown, consisting of a marginal bead, B, a perfectly-plain surface, C, at its upper half or wider end, and a 45 series of tapered parallel corrugations, D, increasing in length toward the middle one, and a transverse band crossing the corrugations at the narrowest portion of the shank of the handle, as shown and described.

AUSTIN FREDK. JACKSON.
